UNITED STATES PATENT OFFICE.

HERMAN A. POPPENHUSEN, OF EVANSTON, ILLINOIS.

FURNACE-GRAVE.

SPECIFICATION forming part of Letters Patent No. 753,108, dated February 23, 1904.

Application filed March 12, 1903. Serial No. 147,389. (No model.)

To all whom it may concern:

Be it known that I, HERMAN A. POPPENHUSEN, of Evanston, in the county of Cook and State of Illinois, have invented certain new and useful Improvements in Furnace-Grates; and I do hereby declare that the following is a full, clear, and exact description thereof, reference being had to the accompanying drawings, and to the letters of reference marked thereon, which form a part of this specification.

This invention relates to fuel-feeding devices for furnaces of that kind having an endless traveling grate by which fuel delivered at the feed-opening of the furnace is fed inwardly or advanced through the furnace while combustion is taking place, and more especially to features of construction in the frame by which the operative parts of the grate are supported.

The invention consists in the matters hereinabove described, and pointed out in the appended claims.

In the accompanying drawings, illustrating my invention, Figure 1 is a view in side elevation of a traveling chain grate and its supporting-frame. Fig. 2 is a front view of the frame with the belt shown in cross-section. Fig. 3 is a detail cross-section through one of the side plates of the grate-frame, taken on line 3 3 of Fig. 1. Fig. 4 is a like section taken on line 4 4 of Fig. 1. Fig. 5 is a like section taken on line 5 5 of Fig. 1. Fig. 6 is a detail view showing the inner face of the rearmost section of one of the side plates of the grate-supporting frame. Fig. 7 is a detail view showing the inner face of one of the forward sections of one side of the side plates of the grate-supporting frame. Fig. 8 is a detail side view of one of the bearing-blocks for the upper supporting-rollers. Fig. 9 is a detail cross-section of the upper part of one of the side frame-plates, taken through one of the seats for the bearing-blocks.

In the said drawings, A A indicate the side walls of a boiler or other furnace, B an endless belt or chain grate, and C C' horizontal shafts located at the front and rear ends of the grate and provided with sprocket-wheels C' C'', over which the endless-belt grate B is trained and by which the same is supported.

The grate-supporting shafts C C' are mounted in the opposite ends of a supporting-frame, which in the construction illustrated is mounted on wheels and is adapted for insertion into the furnace or removal from the same. Said frame embraces vertically-arranged parallel members, each of which consists of a forward plate or section D and a rear plate or section D'. The longitudinal frame members are connected with each other by main cross-girders D² 60 D³, Figs. 6 and 7, located between and attached at their ends to the forward and rear plates D and D'. The side walls of the furnace are provided with recesses to receive the side frame-plates D' D', and at the bottoms of the 65 said recesses are located supported rails a a, on which rest the supporting-wheels E E of the grate-frame. Said supporting-wheels are attached to axles E' E', which have bearing at their ends in the lower edges of the frame- 70 plates D D'.

The plates D D' of the grate-supporting frame are shown as made of cast metal and as bolted rigidly to each other at their meeting edges. The rear plates D' D' form the 75 inner and main part of the longitudinal frame members, which are located inside of the front wall of the furnace when the frame is in its operative position. The forward plates D D form the forward part of said side members, 80 which are located outside of the front wall of the furnace and are extended upward above the level of the rear sections D to form the side wall of a hopper which is located above the forward end of the traveling grate B and 85 by means of which the fuel is fed to the said grate. The shaft C is shown as provided with gear-wheels C', and a shaft C³ is mounted in the plates D D. Said shaft C³ and gear-wheels constitute part of a device for actuating the 90 chain grate. The rearmost section D' of one of the side members is shown in detail in Fig. 6 and the forward section D in Fig. 7. It is to be noted, however, that the making in two sections of the lateral frame members is 95 merely a matter of convenience in construction and that so far as the present invention is concerned said lateral frame members may be cast in a single piece. Each of the main longitudinal parts or sections D' of the frame 100

are made of girder form or flanged at their upper and lower margins to give stiffness or rigidity thereto, said frame members consisting of flat vertically-arranged web portions d , 5 provided at their upper edges with inwardly-directed horizontal flanges d' and at their lower edges with like inwardly-directed horizontal flanges d'' . Said frame-member sections D' are also provided with end and intermediate vertical flanges d^3 d^3 and d^4 d^4 , which extend inwardly from the web portions thereof and are joined at their upper and lower edges to the upper and lower horizontal flanges d' d'' .

The grate B illustrated is a chain grate similar to those heretofore used and consists of a plurality of relatively short grate-bars, which extend longitudinally of the grate and are pivotally connected with each other to form a chain or endless belt. The grate illustrated is 15 formed by two sets or kinds of said grate-bars, of which those marked D' are adapted to engage the several sprocket-wheels C^6 C' and may be called "driving-bars," while those marked B^2 constitute the greater part of the 20 fuel-supporting surface of the grate and are located between the driving-bars.

The sprocket-wheel shaft C at the front end of the grate is mounted at its ends in bearings c c , formed on the forward plates or castings D D, the inner parts of said bearings being formed by the recesses in the front margins of the plates and the outer parts of said bearings by means of caps c' c' , bolted to the said plates. The rear sprocket-wheel 30 shaft C' is mounted at its ends in bearing blocks or boxes F, which are mounted to slide horizontally on guide-brackets D³, which project from the rear ends of and are cast integral with the rear sections of the lateral frame 35 members. Said brackets D³ are shown as having the form of vertical webs provided with horizontal top flanges, the side margins of which form guide-ribs for the blocks F, which latter are provided with lateral guide-grooves 40 engaging the said flanges. Provision is made for adjusting the position of the bearing-boxes F so as to adjust the shaft C' horizontally, as may be necessary, for tightening the chain grate. Devices for this purpose 45 herein shown consist of set-screws f, said set-screws f being arranged horizontally and inserted in the sides of the bearing-boxes F nearest the adjacent ends of the frame-plates and having flat-sided heads which bear against 50 vertical surfaces on the ends of said frame-plates, so that by turning said set-screws the boxes may be shifted backwardly on the guide-flanges of the brackets, with the result of shifting rearwardly the said shaft C', and thereby 55 tightening the chain grate. The adjusting devices described may be applied as well to the forward sprocket-shaft C as to the rear shaft.

For the purpose of supporting or sustaining 60 the horizontal parts, laps, or runs of the

grate between the sprocket-wheels the frame is provided with a plurality of horizontally-arranged rollers G and H. The rollers G are located below the upper part or run of the belt and the rollers H are located below the 70 lower part or run of the belt. The rollers G at the top of the carriage are provided at their ends with journals or trunnions g, which engage in bearing-blocks G', which rest upon the upper marginal flange d' of the side frame 75 members. Sockets or seats for said bearing-blocks are formed by means of transversely-arranged vertical arms or flanges d^6 d^6 , cast upon the said flanges d' and rising from the upper surface of the same. 80

The bearing-blocks G are shown as made of a plurality of flat faces arranged at uniform distances from the central axes of the rollers, so that the blocks may be placed in the sockets on the frame members with either side 85 thereof uppermost. In the particular construction shown said blocks are made octagonal in form and are adapted to be placed in the sockets formed by the flanges d^6 d^6 with either face thereof upward. This construction enables the bearing-blocks to be turned or reversed in case of wear of the surfaces in contact with the parts which support them, so as to bring new surfaces thereof in contact with said parts. To hold the bearing-blocks from movement in the direction of the axes of the rollers, the supporting-surfaces of the sockets and the bearing-blocks are provided with interfitting grooves and flanges arranged transversely with respect to the 90 rollers or longitudinally of the frame members. Preferably, and as shown, the flanges d' of the frame members are provided on their upper surfaces between the transverse flanges d^6 with longitudinal ribs d , which enter and fit within grooves or notches g', formed in the said blocks G'. Like grooves g are formed in all of the side faces of the bearing-blocks, so that said blocks will be engaged by the ribs d when turned to bring 95 either side downward. The lowermost supporting-rollers H are similarly provided with trunnions h, which engage bearing-blocks H', which are made with uniformly-disposed flat faces like the bearing-blocks G' above described. Said bearing-blocks H' are adapted to rest upon the lower horizontal flanges d^2 of the side plates, which latter are provided with rectangular apertures d^8 opening through the outer faces thereof to receive the outer 100 portions of said bearing-blocks. For holding the said bearing-blocks in place vertical flanges d^9 are located on the lower flange d^2 at one side of the seats for the said bearing-blocks, said flanges rising from the said 105 lower flanges d^2 and projecting inwardly from the said web portion d of the side plate, while the main vertical flanges d^4 , hereinbefore referred to, are located at the opposite sides of said seats, so that said flanges d^9 d^4 together 110

form the side walls of the seats or sockets to receive and hold in place the said bearing-blocks H' . Longitudinal ribs d^0 rise from the top surface of the lower flange d^2 between the flanges d^0 and d^1 and are adapted to engage grooves h' in the flat faces of the bearing-blocks H' , so as to hold said bearing-blocks from movement in a direction endwise of the rollers. By reason of the octagonal form of the bearing-blocks H' the same are made reversible or are capable of being partially rotated to bring new bearing-surfaces in contact with the sides and bottoms of the recesses, to which they are held in the same manner as before described in connection with the upper bearing-blocks G' .

In the construction illustrated the lower longitudinal stiffening-flanges on the side plates D' of the grate-supporting frame are directed inwardly from the vertical or web portions of said members, and the lower lap or run of the chain-grate is located at a considerable distance above the level of said inwardly-directed flanges. A general advantage in the operation of the grate is gained by this feature of construction, whether the bearings for the supporting-rollers H are supported on the side members in the particular manner shown or otherwise, as may be understood from the following.

In grates of this character it is highly desirable that all of the air entering beneath the upper lap of the grate, on which the burning fuel rests, should pass through said upper lap of the grate, and provision is usually made to prevent the upward passage of air between the side edges of the upper lap and the wall of the furnace by extending inwardly the said side wall above the recesses in which the side plates are located, so the latter will stand close to the side edges of the said upper lap of the grate. In the construction illustrated the projecting part of the walls above said recesses are supported by means of longitudinal metal plates A' , Figs. 3, 4, and 5, the margins of which are located a short distance only from the side margins of the said upper lap of the grate. It is also highly desirable in grates of this character that air entering the ash pit or space below the lower lap or run of the grate be freely admitted to the under surface of the upper lap thereof. The air which passes through the lower lap of the grate is not sufficient for this purpose, because the spaces afforded for the passage of air in the lower lap or run are no greater than those in the upper lap and it is found that much better results be obtained in combustion by providing a much greater area for the entrance of air to said upper lap than is alone afforded by said openings in the lower lap. By locating the vertical or web portions of the side plates or members of the frame closely adjacent to the side walls of the furnace and by so locating the lower stiffening-

flanges d^2 d^3 with respect to the side edge of the lower lap of the grate that the said side edges shall be considerably above the level of said flanges longitudinal openings or spaces are provided at either side of the said lower lap equal in width to the distance between said side edges of the lower lap and the inner faces of the web portions d of the said side members for the upward passage of air from the space beneath the lower lap to the space above said lower lap, as indicated by the arrow in Fig. 3. These longitudinal spaces or openings afford a very considerably greater area of openings for the ingress of air to the space below the upper lap of the grate over that afforded by the openings in the lower lap alone, and greatly in excess of that afforded in the earlier construction, wherein the side members of the supporting-frame have outwardly-directed stiffening-flanges, and the side margins of the lower lap of the belt are in consequence located closely adjacent to the vertical or web portion of the said side members. The said side members of the grate-supporting frame are shown provided with openings in the web portions thereof which are made of considerable size and are adapted to permit inward passage of such air as may enter the space between the lower margins of the said side members and the adjacent surface of the said side walls A of the furnace-wall. While the air thus entering through the openings in the side members will supplement that which enters between the side edges of the lower lap of the grate and the web portions of said side frame members, as above described, yet it is very small in quantity compared with that which passes around the side margins of the lower lap by reason of the openings afforded for this purpose through the construction above described.

While the free ingress of air to the space below the upper lap of the grate is highly desirable in the main part of the grate or that on which the principal part of the burning fuel rests, yet at the rear end of the grate where the fuel is nearly consumed it is desirable that less supply of air should be furnished in order that the air may not escape too freely through the grate at such rear end of the same where the mass of fuel has become thin by reason of the combustion thereof and where in some cases the grate may be bare or nearly except for small quantities of ashes and clinkers that may remain unconsumed thereon. At the rear end portion of the grate, therefore, I so construct the parts as to prevent access of air between the side members of the supporting-frame and the side margins of the lower lap of the grate as follows: For a considerable distance forward from the rear ends of the side frame members the web portions of the said side members are offset inwardly, so as to bring them close to the side edges of the lower lap of the grate, the offset parts

rising from the inner edges of the flanges d^2 to a point opposite the lower margin of the lap of the grate, as clearly shown in Fig. 5. The side member in its part above the portion 5 of the web are, moreover, without any openings. By this construction a narrow space only is afforded between the parts d^1 d^1 of the said webs d and the side margins of the lower lap at the rear part of the grate, so that 10 the supply of air is practically cut off at these points, while no air is admitted through the webs d themselves. As a consequence the supply of air to the extreme rear end of the grate is limited to that which may flow rear- 15 wardly under the upper lap of the grate from the forward part thereof, the amount of air which passes through the rear end portion of the upper lap and the downwardly-moving part of said upper lap which passes around 20 the rear sprocket-wheel being so greatly reduced as to have little effect upon the air-supply furnished to the fuel resting on the forward or main part of the grate.

I claim as my invention—

- 25 1. The combination of an endless traveling grate and a supporting-frame therefor having longitudinal side members, the lower lap of the grate being located above the level of the lower edge of said side members with their lower edges separated from the side members to afford longitudinal air-inlet openings between the side margins of said lower lap and the said side members of the frame, for the passage of air to the upper lap of the grate, 30 and said side members at the rear part of the grate being inwardly offset and located closely adjacent to the side edges of said lower lap to lessen the air-supply at such rear part of the grate.
- 35 2. The combination of an endless traveling grate, a supporting-frame therefor, having longitudinal side members and furnace side walls provided with recesses to receive said side members; said side members of the frame embracing vertical, web portions which are located closely adjacent to the furnace side walls and are provided with lower, inwardly-extending, horizontal stiffening-flanges and the lower lap of the grate being located above the 40 level of said stiffening-flanges, supporting-rollers for said lower lap of the grate, and bearing-blocks for said rollers which rest on the top of said stiffening-flanges.
- 45 3. The combination of an endless traveling grate, and a supporting-frame therefor having longitudinal side members which embrace vertical, web portions, provided with lower, inwardly-extending longitudinal stiffening-flanges, the lower lap of the grate being located above the level of said stiffening-flanges to afford longitudinal openings for admission 50 of air to the upper lap of the grate and said web portions of the side members at the rear part of the grate being inwardly offset and located closely adjacent to the side edge of said

lower lap to lessen the air-supply at such rear portion of the grate.

4. The combination of an endless traveling grate, a supporting-frame therefor having longitudinal side members, which embrace vertical web portions provided with upper and lower, horizontal, inwardly-extending stiffening-flanges, the upper lap of the grate being located above the level of the upper stiffening-flanges and the lower lap of the grate being 75 located above the level of the lower stiffening-flanges, supporting-rollers for the upper and lower laps of said grate and bearing-blocks for said rollers which rest upon and are supported by said upper and lower flanges. 80

5. The combination of an endless traveling grate, a supporting-frame therefor having longitudinal side members which are provided with vertical web portions having horizontally, longitudinal, inwardly-extending stiffening-flanges, supporting-rollers for the grate, and bearing-blocks for the said supporting-rollers, said frame members being provided with sockets to receive the bearing-blocks formed by means of transverse flanges which 85 rise from the said longitudinal flanges. 90

6. The combination of an endless traveling grate, a supporting-frame therefor having longitudinal side members which are provided with vertical web portions having horizontally-arranged, longitudinal stiffening-flanges, supporting-rollers for the grate and bearing-blocks for said supporting-rollers, said frame being provided with sockets to receive the bearing-blocks formed by means of transverse 95 flanges which rise from the said longitudinal flanges, said bearing-blocks having a plurality of flat faces at uniform distances from the central axis of the rollers to enable the said blocks to be placed in said sockets and a plurality of 100 positions. 105

7. The combination of an endless traveling grate, a supporting-frame therefor having longitudinal side members which are provided with vertical web portions having horizontally-arranged, longitudinal stiffening-flanges, supporting-rollers for the grate and bearing-blocks for the ends of the said supporting-rollers, said frame members being provided with sockets to receive the bearing-blocks 110 formed by means of transverse flanges which rise from the said longitudinal flanges and said bearing-blocks and the said sockets being provided with interfitting grooves and projections to hold the bearing-blocks from movement in a direction endwise of the rollers. 115

8. The combination of an endless traveling grate, a supporting-frame therefor having longitudinal side members which are provided with vertical web portions having horizontally-arranged, longitudinal stiffening-flanges, supporting-rollers for the grate, and bearing-blocks for the ends of the said supporting-rollers, said frame being provided with sockets to receive the bearing-blocks formed by 120 125 130

means of transverse flanges which rise from the said longitudinal flanges, said bearing-blocks being provided with a plurality of flat faces arranged at uniform distances from the 5 central axes of the rollers, all of the flat faces of the blocks and the said sockets being provided with interfitting grooves and ribs to hold the blocks from movement in a direction endwise of the rollers.

10 9. The combination of an endless traveling grate, a supporting-frame therefor having longitudinal side members which embrace vertical web portions having lower inwardly-extending horizontal stiffening-flanges, supporting-rollers at the lower lap of the grate, bearing-blocks for said rollers which rest upon and are supported by the said horizontal,

lower stiffening-flanges, said lower stiffening-flanges being provided with transverse flanges which rise from the same to form sockets to 20 receive the said bearing-blocks and the vertical, web portions of the side members being provided with openings opposite said sockets to receive the outer ends of said bearing-blocks.

25 In testimony that I claim the foregoing as my invention I affix my signature, in presence of two witnesses, this 7th day of March, A. D. 1903.

HERMAN A. POPPENHUSEN.
